FIG. 1 is a front, left-side, top perspective view of a device
for radio frequency ablation showing our new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a front, left-side, top perspective view thereof,
with the display panel flipped upwards;

FIG. 9 is a front view thereof, with the display panel flipped
upwards;

FIG. 10 is a back view thereof, with the display panel flipped
upwards;

FIG. 11 is a left-side view thereof, with the display panel
flipped upwards;

FIG. 12 is a right-side view thereof, with the display panel
flipped upwards;

FIG. 13 is a top view thereof, with the display panel flipped
upwards; and,

FIG. 14 is a bottom view thereof, with the display panel
flipped upwards.

The equal length broken lines in the drawings depict portions
of the device for radio frequency ablation that form no
part of the claimed design.
